121,595

DESIGN FOR A VANITY CASE

Paul L. Menn, Los Angeles, Calif.

Application November 15, 1939, Serial No. 88,307

Term of patent 7 years

To all whom it may concern:

Be it known that I, Paul L. Menn, a citizen of the United States, residing at Los Angeles, in the county of Los Angeles and State of California, have invented a new, original, and ornamental Design for a Vanity Case, of which the following is a specification, reference being had to the accompanying drawing, forming part thereof.

showing my new design, the cover being closed, and

Figure 2 is a perspective view of the vanity case showing my new design, the cover being open.

I claim:

The ornamental design for a vanity case, as shown.

PAUL L. MENN.
